(57) **CLAIM**

The ornamental design for a roll-up item organizer and tote, as shown and described.

DESCRIPTION

FIG. 1 is a front perspective view of a roll-up item organizer and tote;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the roll-up item organizer and tote shown in an alternate configuration and in environmental use;

FIG. 9 is a front view of the roll-up item organizer and tote shown with an unclaimed optional pattern thereon;

FIG. 10 is a rear view of the roll-up item organizer and tote shown with an unclaimed optional pattern and logo thereon; and,

FIG. 11 is a top perspective view of the roll-up item organizer and tote shown in a rolled-up configuration.

The broken lines showing portions of the design are for illustrative purposes only and form no part of the claimed design.

1 Claim, 8 Drawing Sheets
